UNITED STATES PATENT OFFICE.

JOHN B. GLOWACKI, OF CHICAGO, ILLINOIS.

ADJUSTABLE HANDGRIP FOR CRUTCHES.

Application filed January 3, 1922. Serial No. 526,617.

To all whom it may concern:

Be it known that I, JOHN B. GLOWACKI, a citizen of the Republic of Poland, and a resident of the city of Chicago, in the county of Cook and State of Illinois, have invented certain new and useful Improvements in an Adjustable Handgrip for Crutches; and I do hereby declare that the following is a full, clear, and exact description of the same, reference being had to the accompanying drawings, and to the numerals of reference marked thereon, which form a part of this specification.

This invention relates to hand grips such as are used in crutches.

It is an object of this invention to provide an improved grip of the type which may be readily adjusted lengthwise of the crutch.

It is a further object of this invention to provide a grip which may be secured to the crutch at any point without marring the wood.

It is a further object of this invention to provide an arrangement whereby the nuts by which the grip is tightened will be kept in operative relation to the clamps that secure the grip to the longitudinal member of the crutch.

Other and further important objects of the invention will be apparent from the disclosures in the drawings and specification.

The invention (in a preferred form) is illustrated in the drawings and hereinafter more fully described.

On the drawings:

Figure 1 is a side view of a crutch equipped with this adjustable hand grip.

Figure 2 is a transverse section of the crutch showing the hand grip applied thereto.

Figure 3 is a section through the center of the hand grip.

Figure 4 is a section upon the line 4-4 of Figure 3.

Figure 5 is a section upon the line 5-5 of Figure 3.

Figure 6 is a section upon the line 6-6 of Figure 3.

Figure 7 is a view of the clamping means detached from the crutch.

As shown on the drawings:

The crutch consists of the usual arm rest 1, foot piece 2 and longitudinal members 3. Adjustably mounted upon the longitudinal members 3 is a hand grip 4 comprising a

handle 5 mounted upon a shaft 6. As shown in Figures 3 and 6, the central part of this shaft is square in order that it may be rotated by rotating the handle 5. Each end 60 of the shaft 6 is cylindrical and screw-threaded as shown at 7 and 8. One of these threads is right-handed and the other left-handed in order that the sleeves 9 and 10 mounted thereon shall be made to approach 65 one another or be driven away from one another by rotating the handle. The outer ends of these sleeves are provided with hexagonal flanges 11.

The longitudinal members 3 are each 70 clasped by a clamping member 12 which consists of a plain part 13 and two curved ears 14. The curved ears fit the curved surface of the longitudinal members 3 which are of the usual half-round form. The edges of 75 the curved ears are also curved in order that the widest part of the ears shall be at the junction with the plain portion 13. In the center of the plain portion 13 the clamping member is offset to form a hexagonal 80 pocket 15 which is to receive the hexagonal head 11. The central portion of the hexagonal offset part of the clamping member has an aperture 16 through which the shaft 6 passes.

The end of the shaft 6 is cup-shaped as shown at 17 to afford an edge which shall give a firm bearing against the wood of the side members 3. The opening 16 has a width at right angles to the plane of the 90 longitudinal members 3 sufficient to accommodate the shaft 6, but its width in the plane of the members 3 is made greater than this in order that there may be room for play between the shaft and the upper and lower 95 edges of this opening.

The handle 4 has at each end a recess 18 and in these recesses are seated springs 19. One end of these springs bears against the inner end of the socket 18. The other end 100 of the springs bears against the raised portion 15 of the clamping member 12.

In assembling the device, the handle 5 is first placed upon the shaft 6, preferably with a driving fit. The springs 19 are then placed 105 in the sockets 18. Then the sleeve members 9 and 10 are placed through the openings 16 in the clamping members 12, with the hexagonal ends 11 seated in the hexagonal pockets 15. The sleeves 9 and 10 with the 110 clamping members 12 attached are then screwed onto the ends of the shaft 6 until

the springs 19 are compressed sufficiently to insure the heads 11 staying in the pockets 15. This work is done before the arm rest 1 is applied to the upper end of the crutch. Next, 5 the assembled hand grip is put into the crutch with the members 12 sliding over the members 3. Then the arm rest 1 is secured at the top of the crutch. The hand grip is slid along the members 3 until the position 10 suitable for the patient is found, and the handle 5 is then rotated in the direction to draw the sleeves 9 toward one another. During this rotation the spring 19 holds the members 12 apart sufficiently to insure that 15 the heads 11 will remain in the pockets 15.

As the sleeves 9 approach one another they draw the members 3 toward one another until the ends 17 of the shaft 6 contact with the inner faces of the members 3. 20 Any further rotation of the handle 5 tightens the grasp of the clamp members 12 upon the longitudinal members 3. The pressure against the curved side of the members is by means of the ears 14, and the pressure against the opposite face is by means 25 of the ends 17 of the shaft 6. The latter pressure is very effective in preventing the hand grip from moving longitudinally of the members 3 because the cup shape of the 30 end 17 makes this pressure come on a line only instead of over a surface. Thus the hand rest is effectually held without the wood of the members 3 being penetrated enough to make any serious disfigurement.

35 When it is desired to loosen the clamps in order to position the hand grip at a different height, the handle 5 is turned in the opposite direction, with the result that the sleeves 9 move away from one another. 40 This relieves the pressure of the ears 14 upon the outer face of the longitudinal members 3 and permits said members to move away from one another. At the same time it moves the members 3 away from the 45 ends 17 of the shaft 6 so that when the longitudinal movement of the hand grip takes place these ends do not scrape the wood.

The springs 19, by keeping the plain face 50 13 of the members 12 against the plain face of the longitudinal members 3, insures that the clamping members will follow the curving shape of the members 3 in this motion. If the handle 5 should be rotated too far 55 in this direction, the plain faces 13 would press against the longitudinal members 3 sufficiently to make it difficult to turn the handle 5. Thus the patient, or whoever is operating the device, is warned against further rotation of the handle 5 in this direction long before the travel of the sleeves 9 covers the distance through which the springs 19 can expand. Consequently during 60 the whole travel the heads 11 are dependably kept within the pockets 15. When the

handle has been so adjusted that the clamping members are loose upon the longitudinal members 3, the grip may be moved up or down until the desired height is secured. Since the longitudinal members 3 are not 70 straight and not parallel the plain faces 13 of the clamping members 12 must tilt relative to the shaft 6 in order to seat themselves against the curved inner surfaces of the longitudinal members 3. This tilting 75 movement of the clamping members 12 relative to the shaft 6 is permitted because of the play between the shaft and the upper and lower sides of the opening 16.

I am aware that many changes may be 80 made and numerous details of construction may be varied through a wide range without departing from the principles of this invention, and I therefore do not purpose limiting the patent granted otherwise than 85 necessitated by the prior art.

I claim as my invention:

1. In a hand grip for crutches, a threaded shaft, a clamping member, a sleeve connecting said shaft and said member, and a 90 spring for keeping said clamping member and sleeve in operative relation.

2. In a device of the class described, a clamp, a pocket integral with said clamp, a shaft traversing said pocket, sleeves 95 threaded on said shaft and having heads engaging the walls of said pockets, and a spring maintaining said pockets against said heads.

3. In a device of the class described, a 100 clamp, a pocket in said clamp, the bottom of said pocket having an opening, a shaft traversing said opening, a sleeve threaded on said shaft and occupying said opening, the dimensions of said opening in one direction being greater than those of said sleeve.

4. In a crutch, a hand grip, clamps at each end of said hand grip securing it to the crutch, said clamps being pivotally 110 mounted to tilt upon said hand grip.

5. In a crutch, two wooden supporting members each having a plane face and a rounded face, a hand rest forming a cross piece between the plane faces of said supporting members, a rod of noncircular cross-section extending longitudinally through said hand rest, a fixture of sheet metal having a plane surface on one side bearing against the plane surface of one of said 115 supporting members and curved surfaces adjacent to said plane surface partly enclosing the rounded face of said supporting member and forming the other side of said fixture, the edges of said curved surfaces 120 farthest from the plane surface being separated, said fixture having a socket upstanding from the plane side, a sleeve non-rotatably mounted in said socket and having threaded connection with said rod, and re- 130

silient means for maintaining the non-rotatable connection between said sleeve and said socket.

6. In a crutch, two longitudinal supporting members, a hand rest forming a cross-connection between said members, said hand rest comprising a handle, a screw-threaded shaft through said handle, means mounted upon each end of said shaft for grasping 10 said longitudinal supporting members, and springs for holding said grasping means against said supporting members.

7. In a device of the class described, a

clamp, a socket integral with said clamp, a threaded sleeve having a head, and means 15 for maintaining said head in contact with the bottom of said socket and away from the objects grasped by said clamp.

In testimony whereof I have hereunto subscribed my name in the presence of two 20 subscribing witnesses.

JOHN B. GLOWACKI.
